UNITED STATES PATENT OFFICE.

JOHN RITCHIE, OF NEW YORK, N. Y.

LATCH FOR AUTOMOBILE-DOORS.

1,253,530.

Specification of Letters Patent. Patented Jan. 15, 1918.

Application filed March 2, 1917. Serial No. 152,027.

To all whom it may concern:

Be it known that I, JOHN RITCHIE, citizen of the United States, residing at New York, in the county of New York and State 5 of New York, have invented certain new and useful Improvements in Latches for Automobile-Doors, of which the following is a specification, reference being had therein to the accompanying drawing.

10 This invention relates to improvements in automobile doors, and has for its primary object the provision of means for latching the doors in closed position including concealed releasing means having actuating 15 means exposed for actuation, but the character of which is such as not to be ordinarily observed by others than the user of the machine, all to the end that the machine is better protected against unauthorized entry 20 through the doorway.

The preferred embodiment of the invention embraces an actuating means for the door latch formed and arranged in simulation of a part of the door structure to exhibit a correspondingly misleading appearance to one casually viewing the same.

That the details in construction and arrangement of parts of a practical construction made in accordance with the invention 30 may be readily understood, I have illustrated in the accompanying drawings, forming part hereof, the preferred embodiment of the invention to which I have already alluded. These drawings are of course intended to be considered in connection with the specific description thereof hereinafter contained.

In the drawings:

Figure 1 is a side elevation of a fragmentary portion of a closed body of a vehicle possessing the invention, the window or glass panel portion of the door in this view being raised, and the outer wall of the lower panel being broken away to show the locking mechanism;

Fig. 2 is an edge view of the door;

Fig. 3 is a horizontal sectional view on the line X—X of Fig. 1, with the window lowered into the hollow bottom section or panel; and,

Fig. 4 is a vertical sectional view.

Referring more specifically to the drawings wherein the same reference letters designate corresponding parts in the several

views, A represents the frame or casing of 55 the doorway, and B the door hinged near its upper and lower ends, as at C to one side of the frame in the customary manner.

D is the lower panel or portion of the door, the same being of hollow formation, 60 in that it has front and rear walls, as shown, between which the vertically slideable window or glass panel E, provided with a suitable frame F working between guides G, may be dropped and inclosed as occasion may re- 65 quire to convert the closed car into an open car. The free edge of the lower portion D of the door opens outwardly, and is normally closed by a plate H secured thereto by screws J, this plate being provided with a 70 bolt opening K.

Formed integrally with this plate H and extending inwardly immediately adjacent to the front wall of the lower portion D of the door is a thin plate L to which the latching parts and means for releasing the latter are secured. These will now be defined.

M is a latching bolt of any convenient type adapted to coöperate with a keeper N on the adjacent side of the frame A, this 80 bolt reciprocating back and forth through the opening K in the plate H previously referred to and guided by flanges O struck inwardly from said plate above and below the bolt. A stop pin P over which a slotted 85 portion Q in the lower edge of the bolt takes, limits the movement of the bolt in both its outward thrust or retracted positions.

The inner end of the bolt is pivotally connected as at q, to a vertically disposed lever R, pivoted to the supporting plate L, as at r, and carrying at its upper end which is offset outwardly as illustrated, a pair of separated anti-friction rollers S, for a purpose as will soon appear. At the pivotal junction 95 between the bolt Q and lever R I provide an anti-friction roller T adapted to constantly work against an outwardly thrust spring U mounted upon the plate L, as at u, and reinforced by a pin u' behind said 100 spring and also secured to said plate.

The spaced rollers S are adapted to fit in parallel grooved portions v whereby to support, and as required, ride beneath the free end of a manually operable lock controlling 105 device in the nature of an elongated member closed at its outer free end as at V, but branched at its inner end as at V' to provide

engaging members respectively located inside and outside of the window E, when elevated, to permit operation of the latch correspondingly from the inside and outside 5 of the car.

That end of the branched portion V' of the controlling device now under discussion, which lies nearest to the supporting plate L is pivoted to said plate as at W enabling the 10 connected end V of this device to maintain by gravity its position relative to the rollers S.

It will be appreciated that the branched portion V' of the controlling device provides 15 ample space as at Y for the accommodation of the slidable window or panel E.

It is to be further understood that the upper edges of the front and rear wall portions D are grooved to receive the branched 20 portions V' of the controlling device, the grooving being represented at Z, and that the parts are so proportioned and arranged that the upper surfaces of the controlling device are flush with the adjacent surfaces 25 of the upper edges of said wall portions D so that, as best seen in Fig. 2, the entire structure presents the appearance of a sectional rail or edge formation, not suggestive of means for actuating a lock to enable opening and closing of the door. The pressure 30 of the spring U is such as to normally thrust the bolt M outwardly into the keeper N to lock the door closed, correspondingly maintaining the rollers S at their highest position 35 with the controlling device V—V' in its horizontal or flush position, and the tension of the spring is such as to require substantial pressure to release the bolt, necessitating the engagement of the said controlling 40 device V—V' at a point considerably removed from the pivot W thereof, and near the outer or free end of said device. During the back and forth movements of the bolt and the consequent shifting of the operating 45 parts, the rollers S and T facilitate the operation and prevent noise.

As stated, it will be appreciated that whether or not the window E being closed or open, the door may be actuated from 50 either outside or inside the car by merely pressing the fingers over the upper edge of the bottom portion D and depressing said fingers to correspondingly depress the free end of the controlling device V—V', which 55 in turn, operating through the rollers S at the short end of the lever R, throw the lower and longer end of the lever R inwardly, against the pressure of the spring U and retracting the bolt M from the keeper N, the 60 withdrawing of the pressure of the fingers permitting the parts to immediately assume their normal latching position, and by reason of the usual inner beveled face of the bolt M enabling the lock to automatically recede 65 while the door is being closed and be thrust

outwardly into the keeper when the door is completely closed, after the common practice in this art.

While I have herein disclosed the preferred embodiment of the invention it will 70 be understood by persons skilled in the art to which the invention relates that the same is capable of embodiment in other forms and devices without departing from the spirit or principle of the invention, as may be comprehended by the hereto appended claims. 75

Having thus described the invention, what I claim is:

1. The combination with a door member, of latching means therefor comprising a 80 bolt, means for normally throwing the bolt to locking position, and means for retracting said bolt including an elongated pivoted member lying at the upper edge of the door and adapted to be depressed, for the purpose described.

2. The combination with a door member, of latching means therefor comprising a bolt, means for normally throwing the bolt to locking position, and means for retracting 90 said bolt including an elongated pivoted member lying at the upper edge of the door and adapted to be depressed, and a pivoted lever engaging said member at one end and at its other end engaging the bolt. 95

3. The combination with a door member, of means for latching the same comprising a bolt, means for normally throwing the bolt to latching position, and means for retracting the bolt comprising a pivoted lever engaging the bolt at one end and at its other end being offset, and an elongated pivoted member at the upper edge of the door member engaging said offset end of said lever, substantially as described. 100

4. The combination with a door member and means for latching the same comprising a bolt, and means for shifting the same in one direction including a depressible elongated member at the upper edge of the door 110 member, substantially as described.

5. The combination with a door member and means for latching the same comprising a bolt, and means for shifting the same in one direction including a depressible elongated member pivoted at the upper edge of the door member, substantially as described. 115

6. The combination with a door member and means for latching the same comprising a bolt, and means for shifting the same in 120 one direction including a depressible elongated member pivoted at the upper edge of the door member, and operating connections between said elongated member and the bolt including a sliding engagement between the 125 former and said operating connections.

7. The combination with a door member and means for latching the same comprising a bolt, and means for shifting the same in one direction including a depressible elong- 130

- gated member pivoted at the upper edge of the door member, and operating connections between said elongated member and the bolt including a sliding engagement between the former and said operating connections, said sliding engagement comprising a grooved portion of the elongated member and an anti-friction roller carried by the operating connections.
- 10 8. The combination with a door member, of a latch therefor comprising a bolt, a spring for forcing the bolt outwardly to latching position, means for retracting the bolt including a lever pivoted thereto, and an anti-friction bearing interposed between said spring and said bolt, substantially as described.
9. The combination with a door member, of means for latching the same including a bolt, means for normally throwing the bolt to latching position, and means for retracting the bolt including an elongated depressible member in the upper edge of the door member, and operating connections between said member and bolt including an anti-friction bearing interposed between said elongated member and the adjacent part of the operating connections.
- 10 10. The combination with a door member of hollow formation to accommodate an upper panel, of means for latching the door member in closed position including a bolt, and means for controlling the bolt having branched engaging portions lying at the upper edges of the door member at opposite sides of the panel receiving opening.
11. The combination with a door member of hollow formation to accommodate an upper panel, of means for latching the door member in closed position including a bolt, and means for controlling the bolt having branched engaging portions lying at opposite sides of the panel receiving opening, and operating connections between said branched controlling device and the bolt including a pivoted lever associated at one end with the bolt and at the other end bearing separated anti-friction devices, the adjacent part of the controlling device being grooved for the accommodation of said devices, substantially as described.
12. The combination with a door member of hollow construction to accommodate a slideable panel, of means for latching said door member including a bolt, means for normally throwing the bolt to locking position, and means for retracting the bolt in-
- cluding an elongated branched controlling device lying in part at opposite sides of the opening of said panel, in combination with means for pivotally mounting said branched controlling device at one end, and operating connections between the free end thereof and said bolt.
13. The combination with a door and a panel carried thereby, of latching mechanism for latching the door, and controlling means arranged on each side of the panel and lying at the horizontal upper edge of the door, and a connection between said controlling means and the door latching mechanism.
14. The combination with a door member, of a panel carried thereby, latching mechanism for the door, and means on each side of the panel and lying at the horizontal top edge of the door for controlling said latching mechanism to permit the operation thereof from either side of the panel.
15. The combination with a door member, of a panel carried thereby, latching mechanism for the door, and controlling means on each side of the panel and lying at the horizontal top edge of the door for controlling said latching mechanism to permit the operation thereof from either side of the panel, said controlling means comprising a bifurcated elongated member, and a pivotal support for said member.
16. The combination with a door and a panel carried thereby, of latching mechanism for the door and elongated latch controlling means arranged on each side of the panel and lying at the horizontal upper edge of the door having an operative connection with the latching mechanism, substantially as described.
17. The combination with a door member and means for latching the same, comprising a latching member, and means for shifting the latching member including an elongated member depressible at one end thereof and in operative association with the latching member, said elongated member occupying a position lengthwise of the upper edge of the door member and approximately at said edge.

In testimony whereof I hereunto affix my signature in the presence of two witnesses.

JOHN RITCHIE.
